[57] CLAIM

The ornamental design for a video camera stand, as shown and described.

DESCRIPTION

FIG. 1 is a top plan view of a video camera stand showing my new design;

FIG. 2 is a bottom plan view thereof;

FIG. 3 is a right side elevational view, the left side view being a mirror image thereof;

FIG. 4 is a front elevational view thereof;

FIG. 5 is a rear elevational view thereof;

FIG. 6 is a top plan view of a second embodiment of the video camera stand;

FIG. 7 is a bottom plan view of the video camera stand as shown in FIG. 6;

FIG. 8 is a right side elevational view of the embodiment as seen in FIG. 6, the left side view being a mirror image thereof and the front and rear views being identical to the front and rear views shown in the first embodiment;

FIG. 9 is a top, front perspective view thereof; and,

FIG. 10 is a bottom, rear perspective view thereof.

FIG. 5

FIG. 2

FIG. 1

FIG. 3

FIG. 4

FIG. 7

FIG. 10

FIG. 9
